(57) **CLAIM**

The ornamental design for a coffee tamper as shown and described.

DESCRIPTION

1. Coffee tamper

1.1: Perspective shows a left perspective view of the coffee tamper;

1.2: Front shows a front view thereof;

1.3: Right shows a right view thereof, where a top button is arranged in an upward position;

1.4: Right shows a right view thereof, where the top button is arranged in a depressed position;

1.5: Perspective shows a right perspective view of the coffee tamper;

1.6: Back shows a rear view thereof;

1.7: Top shows a top view thereof; and

1.8: Left shows a left view thereof.

The claimed design represents a coffee tamper for tamping ground coffee. The broken lines show portions of the coffee tamper that form no part of the claimed design.
